UNITED STATES PATENT OFFICE.

RUDOLPH J. WARNER AND JOSEPH SCHAEFER, OF BUFFALO, NEW YORK, ASSIGNEES
TO WARNER JEWELRY CASE COMPANY, OF BUFFALO, NEW YORK, A CORPORATION
OF NEW YORK.

JEWELRY BOX.

Application filed June 24, 1926. Serial No. 118,232.

This invention relates generally to jewelry boxes but more particularly to ring boxes.

One of its objects is to improve the ring-holding or clamping device with a view of simplifying its construction, reducing its cost, retaining and displaying the ring in the required position and adapting it to rings of different sizes.

In boxes of this kind, as hitherto made, the slot which receives and holds the ring is formed in a pad or cushion of wadding covering with the desired material. As wadding has little or no elasticity, the walls of the slot become set by the inserted ring, and if the ring-shank is comparatively wide, the slot is enlarged to such an extent that it will not tightly hold a ring with a narrow shank. It is also difficult to make such wadding-stuffed pads of uniform shape.

20 A further object of our invention is the provision of a block which forms a firm foundation for the ring-holder, which can be cheaply and uniformly produced and which, when covered, presents a neat and attractive appearance.

In the accompanying drawings:—

Figure 1 is a perspective view of a ring-box embodying the invention, with the cover open. Figure 2 is a vertical section of the same on line 2—2, Fig. 1. Figure 3 is a cross section on the correspondingly-numbered line in Fig. 2. Figure 4 is a perspective view of the block carrying the ring-holder. Figure 5 is a vertical longitudinal section of the block and the holder. Figures 6 and 7 are similar sections showing modified constructions of the ring-holder.

Similar characters of reference indicate corresponding parts throughout the several views.

Referring to Figs. 1—5, 10 indicates the body of the box and 11 its hinged cover which parts are preferably stamped of sheet metal, although they may be made of paper, celluloid, or other suitable material. As usual, they are covered with velvet, leather or other appropriate material.

Instead of the usual soft or wadded pad, the box body contains a rigid block 12, preferably in the form of an inverted box-like cup stamped of sheet metal. Its depending rim 13 rests on the bottom of the box, while its top-plate is substantially flush

with the upper edge of the box, being preferably surrounded by the customary neck 14 of the box. The block is snugly fitted into the neck and is covered with any desired decorative material 15, such as velvet or the like. A layer or thin sheet 16 of wadding of substantially the dimensions of the block is usually laid upon it before the covering 15 is applied, the flat top of the block forming a firm and smooth support for the covering.

Formed centrally in the block is a transverse slot 17 containing a holder for a finger ring or other article of jewelry. The mouth of this holder is substantially flush with the top surface of the block, and in its preferred form, illustrated in Fig. 4, consists of a strip 70 of spring steel, approximately as wide as the length of the slot, doubled to form a pair of resilient jaws 18 adapted to clasp the ring-shank frictionally between them. These jaws extend a suitable distance below the top plate of the block and are usually inclined toward the rear of the box to display the jewel of the ring in a forwardly-inclined position to the observer. The jaws are formed at their upper ends with flanges 19, 80 one of which is preferably secured to the top plate of the block 12 by welding or other means, while the flange of the other jaw bears against the underside of said plate and is detached therefrom and free to slide toward and from the other jaw to give the holder a greater range elasticity. This construction adapts the holder to different-sized rings, enabling the same box to be used for a variety of sizes. The slot 17 is wide enough 90 to permit this yieldable action of the movable jaw. The covering material of the block also covers the jaws of the holder, as shown.

Obviously, this spring-holder may be modified in various ways and we do not therefore 95 wish to be limited to the particular construction herein shown and described.

For example, as shown in Fig. 6, the flanges 19^a of the jaws could both be arranged on the upper side of the block; or they could both be located on the underside of its top plate, as shown at 19^b in Fig. 7.

The spring-holder, while affording the advantage of accommodating rings of different sizes will retain its elasticity and not become set, as in ring-boxes having a pad stuffed

with wadding or similar soft material. This flexible or elastic capacity of the holder also allows it to be bent bodily at any desired display angle.

5. Such rigid blocks can be stamped with uniformity and are not more or less irregular in form as is liable to be the case with boxes having a soft or wadded pad, thus rendering them more sightly and attractive.

10. A rigid block of this construction can also be made more cheaply than the soft pads heretofore employed.

We claim as our invention:—

15. The combination with a jewelry box, of a block fitted in the same and consisting of a rigid top plate and a depending rim stamped in one piece, said top plate having a slot, and a ring-holder carried by said plate and having its receiving end arranged in 20 said slot, said holder consisting of a strip of resilient material doubled upon itself to form a pair of jaws, one of said jaws being secured at its free end to the top plate and the other being detached therefrom and free 25 to move bodily relative to its companion jaw.

2. A jewelry box containing a rigid inverted box-like cup having a slot in its top wall, a holder having its receiving end arranged in said slot and consisting of spring

jaws joined at their lower ends, one of said jaws being secured at its upper end to said cup-wall and the other being detached therefrom, and guided for movement relative thereto and to the companion jaw.

3. In a jewelry box, a rigid block adapted to be fitted in the box and having a slot, and a holder consisting of a doubled strip of resilient material forming spring jaws, the receiving ends of the jaws having flanges, one of which is detached from the block 40 while the other is secured thereto.

4. A jewelry box containing a stamped rigid block of inverted cup-form, comprising a top-plate substantially flush with the upper edge of the box and a depending rim resting on its bottom, said plate having a slot, a holder for jewelry depending from said plate and including spring-jaws having their receiving ends arranged in said slot, one of said jaws being secured at its upper 50 end to said top plate and the other jaw being detached therefrom and free to move bodily toward and from the companion jaw, and a covering extending over the block and the holder and into the latter.

RUDOLPH J. WARNER.
JOSEPH SCHAEFER.
